(57) **CLAIM**

The ornamental design for a windshield mountable video camera, as shown and described.

DESCRIPTION

FIG. 1 is a perspective view of a windshield mountable video camera showing my new design;
FIG. 2 is a front elevation view thereof;
FIG. 3 is a rear elevation view thereof;
FIG. 4 is a top plan view thereof;
FIG. 5 is a bottom plan view thereof;
FIG. 6 is a right side elevation view thereof; and,
FIG. 7 is a left side elevation view thereof.

The broken lines depict portions of the windshield mountable video camera in which the design is embodied that form no part of the claimed design.
